UNITED STATES PATENT OFFICE.

ANTON VAN VEEN, OF HARTFORD, CONNECTICUT, ASSIGNOR TO THE FULLER BRUSH COMPANY, OF HARTFORD, CONNECTICUT, A CORPORATION OF CONNECTICUT.

MARKING MACHINE.

Application filed December 9, 1922. Serial No. 605,803.

My invention relates to the class of machines that operate to automatically mark or brand articles with characters of any desired sort, and an object of my invention, 5 among others, is to provide a machine of this type that shall automatically, efficiently and rapidly perform the operations required of it.

One form of machine embodying my invention and in the construction and use of which the objects herein set out, as well as others, may be attained, is illustrated in the accompanying drawings, in which—

Figure 1 is a top view of my improved 15 marking machine.

Figure 2 it a view in front elevation with the driving shaft broken off.

Figure 3 is an end view looking at the 20 left hand end of the machine as shown in Figure 2.

Figure 4 is a view, scale enlarged, through a portion of the machine on a plane passing centrally, lengthwise through the branding or marking head.

25 Figure 5 is a view in section on a plane denoted by the dotted line 5 of Figure 4.

Figure 6 is a side view of the branding or marking head.

Figure 7 is a view in cross section through 30 the marking or branding head and supporting table on a plane passing through the marking or branding dies, parts of the machine underneath said table being broken away.

35 My improved machine shown and described herein may be, as a whole, supported in any desired manner, the machine illustrated embodying a base plate 10 that may rest upon any suitable support. A bearing bracket 11 is secured to and rises from this base plate and is provided at its upper end with bearings 12—13 for a driving shaft 14 that may be rotated in any suitable manner, as by a belt passing about a driving pulley 40 15 secured to said driving shaft. A flanged collar 16 is secured to the end of the driving shaft opposite said pulley, and a marking or branding head 17 is secured to the flange of said collar as by screw bolts 18 passing through spacers 19 by means of which the marking or branding head is spaced from said collar, the bearings 12 and 13 being of sufficient length to rigidly support the marking or branding head and parts secured thereto.

The marking head 17 is provided with markers 20 located on the periphery of the marking head. These markers may be formed in any desired manner, integral with or separate from said head. In the 60 preferred form of construction and as shown herein these markers or branding members are in the form of dies comprising marker bases 21 secured in grooves 22 in the marking head, said grooves being preferably of dovetailed shape to receive said bases of the same shape, and preferably said grooves taper from a certain width at one end to a different width at the other end so that the markers will be tightly wedged as they are driven 70 endwise into said grooves.

The marking head is provided in its interior with any suitable means for heating said head and said markers or branding members to a proper degree for marking 75 purposes. In the structure herein shown this heating member 23 comprises a coil constructed in any ordinary and well known manner to receive a current of electricity to cause said coil to be heated and such heat to 80 be transferred from the coil to the head 17. The structure of this coil is not specifically shown herein as it will be readily understood by those skilled in the art. The opposite ends of the structure comprising said 85 coil are extended out at the end of the head 17 forming terminals 24—25 to which conductors 26—27 are connected.

A case 28 is attached to the end of the head 17, and a neck 29 projects from said case, a cap 30 closing the opening at the outer end of the neck. A bolt 31 extends through said cap, neck, and case, and through the head 17, the end of the bolt being threaded into the shaft 14, as shown in 95 Figure 4 of the drawings, and any suitable means, as a head or a nut, may be employed to secure the bolt against the cap 30. An opening 32 within which said bolt projects in the head 17 is preferably larger than said 100 bolt to provide a space entirely there-around.

An insulator 33 fills the chamber within the case 28 and the neck 29, such insulator being for the purpose of preventing transfer 105 of heat from the head 17 to the case 28 and parts of the mechanism thereon, and such insulator may be composed of any suitable non-heat conducting material, as asbestos. The terminals 24—25 extend into this insula- 11

tor and the conductors 26—27 extend through it and through openings in the side of the neck 29 to the outer side thereof. Dowel pins 34 extend into the facing edges of the head 17 and case 28, and spacers 35 are employed to separate the case from the head. Said spacers may be formed as an integral part of the dowel pins if desired.

The conductor 26 is secured to a conducting collar 36 mounted on an insulating sleeve 37 attached to the neck 29 in any suitable manner, and the conductor 27 is secured to a similar conducting collar 38 mounted on said sleeve.

15 A standard 39 is supported by the base 10 and rises therefrom and has a brush supporting plate 40 secured to its upper end and projecting beyond the side thereof, brush supports 41—42 extending through openings 20 in the projecting part of said plate. Wires 43—44 are secured to the supports 42—41 and brushes 45—46 are yieldingly mounted in any suitable manner in the supports 41—42, said brushes being thus held in yielding contact 25 with the said collars 36—38. By this means a current of electricity is set up from any suitable source (not shown herein) through the members and conductors above described to the heating member 23 and therefrom 30 back to said source in a manner that will be readily understood.

A block 47 is secured to the base 10 and a table supporting bracket 48 is secured to and projects from said block. A table 49 is pivotally attached to said bracket, said table preferably having a groove 50 within which articles 51, as wooden handles, are located and along which they roll, the table 49 being inclined to cause such rolling action. 40 The table is yieldingly supported upon a plunger 52 seated upon a spring 53 in a recess 54 in the block 47, as shown in Figure 7 of the drawings.

Positioning plungers 55 project from the 45 upper surface of the table to intercept the articles 51 and stop their rolling movement in proper position to receive the markers 20, as the latter are rotated with the head 17 above such articles, but in position to 50 come in contact therewith. These positioning members are yieldingly mounted upon springs 56 located in spring cases 57 projecting from the under surface of the table 49, the positioning members projecting upwardly through the table, and as shown in Figure 7 of the drawings.

The operation of the machine will be 60 readily understood, it being noted that the head 17 is so insulated that the heat therefrom will not be communicated to an objectionable degree to other portions of the machine. The positioning members 55 intercept the articles to be marked in such position that the markers 20, as they sweep 65 over the articles, will come in contact with

them and roll them along, the positioning members 55 in this operation being depressed sufficiently to permit the articles to roll over them, and the spring pressed plunger 52 also yielding to enable the table to move downwardly and thus permit the articles to pass underneath the markers, this plunger maintaining sufficient pressure between the articles and the markers to cause the latter to effectively mark or brand said article. 70

The collars 36 and 38 are secured as by set screws, as shown in Figure 4 of the drawings, and in order to effectively secure them in place a shoe 58 is interposed between each collar and the sleeve 37 against which shoes the set screws bind to hold the collars securely in place. 80

While the case 28 and neck 29 projecting therefrom are shown as filled with an insulating material, it is observed that it is not absolutely essential to the invention that said case and neck shall be thus filled, as extremely satisfactory results will be obtained without any filling whatever in said case and neck. 90

In accordance with the provisions of the patent statutes I have described the principles of operation of my invention, together with the device which I now consider to represent the best embodiment thereof; but I desire to have it understood that the device shown is only illustrative, and that the invention may be carried out by other means. 95

I claim:

1. A marking machine including a movably mounted marking member, a table pivotally mounted to support articles to be marked for movement past said marking member, and a positioning member supported by said table to position the end article of a row of contiguously disposed articles in marking position relatively to said marking member, said member being operative to restrain movement of said row of articles with said end article in said marking position. 100

2. A marking machine including a movably mounted marking member, a table yieldingly movably mounted to support articles to be marked for movement past said marking member, and a positioning member yieldingly movably supported by said table to position the end article of a row of contiguously disposed articles in marking position relatively to said marking member, said member being operative to restrain movement of said row of articles with said end article in said marking position. 115

3. A marking machine including a movably mounted marking member, a table mounted in an inclined position to support articles to be marked for rolling movement with respect to said marking member, and a positioning member yieldingly supported by 120

said table to position the end article of a row of contiguously disposed articles in marking position with respect to said marking member and to permit movement of said articles past said marking member, said member being operative to restrain movement of said row of articles with said end article in said marking position.

4. A marking machine including a movably mounted marking member, a table movably mounted to support a row of contiguously disposed articles to be marked, means for yieldingly forcing the table toward said marking member, and a positioning member supported by said table to position the end article of said row relatively to said marking member for movement thereby, said member being operative to restrain movement of said row of articles with said end article in said marking position.

5. A marking machine including a movably mounted marking member, a table movably mounted to support articles to be marked, a plunger, means for yieldingly forcing the plunger against said table, means for limiting movement of the table under the application of said force, and a positioning member supported by said table to position the end article of a row of contiguously disposed articles in marking position relatively to said marking member, said member being operative to restrain movement of said row of articles with said end article in said marking position.

6. A marking machine including a marking member and a table member to support articles to be marked, one of said members being movably mounted to cause rolling movement of said articles past said marking member, and a positioning member supported by said table to position the end article of a row of contiguously disposed articles in marking position relatively to said marking member, said member being operative to restrain movement of said row of articles with said end article in said marking position.

7. A marking machine including a rotatably mounted marking member, a table pivotally mounted to support a row of contiguously disposed articles to be marked for

successive movement of the bottom article in contact with the next article above in the row past said marking member, a positioning member supported by said table and means for retaining said positioning member to limit the movement of said row and including the article being marked, whereby the end article will be placed in the path of movement of a marking member at each operation of the table.

8. A marking machine including a rotatably mounted marking member, a table pivotally mounted to support a row of contiguously disposed articles to be marked for successive movement of the bottom article in contact with the next article above in the row past said marking member, a positioning member yieldingly supported by said table for radial movement with respect to said marking member, and means for retaining said positioning member to limit the movement of said row and including the article being marked, whereby the end article will be placed in the path of movement of a marking member at each operation of the table.

9. A marking machine including a rotatably mounted marking member, a table disposed in an inclined position to support a row of contiguously disposed articles for successive movement of the bottom article in contact with the article next above in the row past said marking member, and a positioning member supported by said table for radial movement with respect to said marking member to thereby prevent movement of the article in the row next to and in contact with the one being marked from movement past the marking point

10. A marking machine including a movably mounted marking member, a table movably mounted to support a row of contiguously disposed articles to be marked, means for yieldingly forcing the table toward the marking member, and a positioning member supported by said table to support the entire row of articles including the bottom article during the marking operation upon the latter.

ANTON VAN VEEN.
